UNITED STATES PATENT OFFICE.

WILLIAM H. CATER, OF CHICAGO, ILLINOIS.

WELL SCREEN.

Application filed December 5, 1923. Serial No. 678,583.

To all whom it may concern:

Be it known that I, WILLIAM H. CATER, a citizen of the United States, residing at Chicago, in the county of Cook and State 5 of Illinois, have invented certain new and useful Improvements in Well Screens, of which the following is a specification.

The present invention concerns well screens or casings of the foraminous or perforated type which are driven or forced down into the ground during the well-sinking operation, the apertures through the casing or screen wall allowing water or other liquids to flow inwardly or outwardly 15 through such wall.

This passage of the liquid through these perforations facilitates the descent of the screen or casing, and it is also used to clean such apertures or slots to free them from 20 obstructions by suddenly forcing the liquid outwardly therethrough.

One object of the invention is the production or provision of an apertured well-screen or perforated casing of this style 25 which by reason of its structural features assists in keeping its slots or openings free from clogging or obstructing materials.

To this end, therefore, the structure is 30 made in such a way as to provide slots which are more or less shielded by parts of the casing during its downward sinking, thereby tending to free the slots from choking 35 or blocking bodies or particles.

In the preferred embodiment of the invention, the slots are made in pairs by deflecting a metal strip out of the plane of the metal sheet forming the casing, leaving slots or openings through the latter along the opposite edges of the strip, each such strip 40 being tapered with its wider end disposed downwardly, thereby providing a pair of upwardly-converging slots or openings.

It will be seen, therefore, that during the sinking or downward forcing of the screen 45 or casing in the usual way by means of an internal pump and suction action around the lower edge of the casing, the wider, lower edges or borders of the outwardly-deflected metal strips cut paths in the surrounding earth slightly wider than the other or upper parts of the strips, thus tending to leave small gaps in the earth around the 50 slots along the edges of such strips.

Stated somewhat differently, these metal 55 strips integral with the sheet-metal casing or screen plow furrows or grooves in the earth

wider than the main portions of such strips, hence tending to keep the dirt, gravel or the like away from direct intimate contact with the metal around or bordering the pairs of 60 converging slots or perforations.

Another object of the new and improved form of structure is to make the sheet-metal screen or casing of substantially uniform strength throughout its length, whereby no 65 part or section is weaker than any other, and hence not more likely to give way, crush or rupture under the rather severe strains and stresses to which it is subjected.

A further purpose of the invention is the 70 provision of a foraminous sheet-metal shell or casing which is easier to force down into the earth than those types of reticulated screens in more common use.

An added aim of the invention is the 75 production of a screen or casing of this form which possesses greater than the customary strength throughout, hence, in some cases permitting the employment of a thinner gauge of metal than has heretofore been 80 usual.

Still another advantage accruing from the employment of the new screen or casing is the certainty of making connection with any 85 water or other liquid vein, no matter how narrow or shallow it may be.

To enable those skilled in this art to have a full and complete understanding of the present invention and the several structural and functional advantages accruing from its 90 use, in the accompanying drawing forming a part of this specification, I have illustrated a desirable and preferred embodiment of the invention, like reference characters being used throughout the several views to designate the same parts.

In this drawing,—

Fig. 1 is a fragmentary elevation of a portion of a well-screen constructed in accordance with the principles of this invention; 100

Fig. 2 is a vertical section, on an enlarged scale, on line 2—2 of Fig. 1, the parts being viewed in the direction indicated by the arrows; and 105

Fig. 3 is a horizontal section, on an enlarged scale, on line 3—3 of Fig. 1, the structure being viewed in the direction designated by the arrows.

Referring now to this drawing, it will be 110 seen that the single-thickness, cylindrical, metal shell 11 comprising the main body of

the screen or casing is provided with a large number of pairs of upwardly-converging openings or slots 12, 12 disposed or arranged generally lengthwise the screen or casing and each pair formed between the edges of the main body of the metal sheet and the opposite margins or borders of a lengthwise-tapered strip or section 13 of the metal sheet, the wider end of such strip being arranged downwardly.

These metal strips or bands and their associated slots or elongated apertures are disposed in longitudinal and transverse rows or lines, as is fully illustrated, and it will be observed that the strips and their complementary slots of each lengthwise row are individually offset longitudinally with respect to the strips and their openings of the rows on opposite sides thereof, with the opposite end portions of each strip and its slots overlapping or extending lengthwise beyond the ends of the adjacent strips, both above and below it, of such adjoining transverse rows.

In this way a screen is provided which is of substantially uniform strength throughout without any unduly weak sections and without any such frail portions coupled with much stronger intervening sections.

Expressed otherwise, the new and improved casing or screen has no imperforate, transverse bands or zones flanked above and below by weaker or more frail slotted or apertured sections, as is more or less customary in the usual practice.

It will be perceived that in this new screen the narrower ends of the strips overlap the wider ends of neighboring or contiguous strips, thus avoiding weakening the metal unduly at any point or location.

During the well sinking or driving operation, at which time the perforated casing, preferably weighted, descends step by step owing to the suction action of the pump used inside of the casing, the lower, larger or wider parts of the outwardly-deflected metal strips force the earth out of the way, so that as the strips and their openings or slots descend in the plowed-out grooves formed by their lower ends, the earth is more or less effectively kept away from direct contact with the margins of the grooves, hence tending to prevent the slots from becoming clogged or stopped up.

Without repeating here the several ad-

vantages incident to the employment of a well screen or casing of the form depicted and illustrated, which has been presented hereinbefore somewhat in detail, it will be seen that all of them are present in the improved and novel structure set forth.

Those skilled in this art will readily appreciate that many minor mechanical changes may be made in the structure illustrated and described without departure from the heart and essence of the invention and without the sacrifice of any of its substantial benefits and advantages.

In so far as the new and improved screen has been set forth above with respect to its advantages, the latter have been confined to the use of the screen or casing after it has been produced, but it is to be observed that, because the deformed or outwardly-pressed metal strips are tapered, they can more readily be separated from the co-operating punches and dies which produce them, by reason of a slight lengthwise movement of the metal sheet with relation thereto, the release of the sheet occurring more easily than in those structures having similar metal strips of uniform width.

I claim:

1. A foraminous sheet-metal well-screen, adapted for descent in the earth during the driving of the well, having a sheet-metal wall equipped with a plurality of spaced longitudinally-tapered lengthwise strips of the metal sheet positioned out of the plane of the sheet, the ends of such strips being integral with the body of the metal sheet, thereby providing two converging slots through the metal along the opposite margins of each strip.

2. A foraminous sheet-metal well-screen, adapted for descent in the earth during the driving of the well, having a sheet-metal wall equipped with a plurality of spaced longitudinally-tapered lengthwise strips of the metal sheet positioned out of the plane of the sheet, the ends of such strips being integral with the body of the metal sheet, thereby providing two converging slots through the metal along the opposite edges of each such strip, the ends of said strips of greater width being disposed toward the lower end of the casing.

In witness whereof I have hereunto set my hand and seal.

WILLIAM H. CATER. [L.S.]
